UNITED STATES PATENT OFFICE.

ALFRED J. KRANK, OF ST. PAUL, MINNESOTA.

ADJUSTABLE BOOTH UNIT.

Application filed May 1, 1924. Serial No. 710,396.

My invention relates to collapsible booth units where it is desired to provide a booth which is made up in a finished form with front, back and side walls, so as to provide a private booth which can be set up about a barber chair at a nominal cost. The booth units are of a simple construction and are adjustable so that a series can be connected together to make up as many booths about the different barber chairs as may be desired. This provides an individual private booth for each barber chair which is a very desirable arrangement in barber shops today, owing to the customs which now prevail in relation to the bobbing of ladies' hair.

It is a feature of the invention to provide a collapsible booth which can be folded into a very small compact state and readily shipped or stored away. Each portion of my booth is of a uniform nature so that the parts are interchangeable for similar parts and can be adjusted so as to vary the size of the booth without changing the general construction of the same.

It is an important feature of the invention to provide a booth which is of such a nature that other similar booths can be added from time to time adjacent the booth already set up about a barber chair because this permits the barber to arrange to have one or more of these booths and to take the same down at any time without affecting the general arrangement of his barber shop. The booths may also be adjusted to the particular arrangement of the particular barber shop. This construction allows the barber to use the four parts making up the individual booth or, if desired, only three of the parts are necessary to make up a private booth for each barber chair. In this instance the back member would be discarded and the booths would be positioned directly around the chair with the sides of the booths extending up to and adjacent the mirror which ordinarily extends along the wall of the barber shop.

My booths are equally adaptable to beauty and hair dressing parlors, and are most desirable because of the fact that they can be added to or changed as to size when desired. The compact manner in which the booths can be collapsed forms an important feature of my invention because it permits the same to be folded flat into a small pack-

age which can be shipped very readily, at a nominal cost.

A feature of the invention includes the particular construction of the members making up the booth unit. The front member is the same for each booth, while the side members are all the same, which is also true of the back members. The side and front members have door openings which can be made of less dimension by removing a portion of the top member extending across the door opening, so that the members of the unit fit closer together.

All the features of the invention will be carefully and fully described, together with the novel construction; and, in the drawings forming part of this specification,

Figure 1 is a perspective view of a series of my booth units set up ready for use.

Figure 2 is a plan view of the same illustrating the chairs in position within the booths as they would appear in use.

Figure 3 is a transverse section on the line 3—3 of Figure 2, in an enlarged scale, illustrating only a portion of the members of the booth units.

Figure 4 is a transverse section on the line 4—4 of Figure 2 illustrating a detail sectional part of the front of the units, a portion of which illustrates the top edge of the unit in plan view.

Figure 5 is a perspective view illustrating one of my booth units collapsed into a compact state.

Figure 6 is a side elevation of one of the side members of my booth unit.

Figure 7 is a side elevation of the front member of my booth unit.

Figure 8 is a side elevation of the back member of the booth unit.

In the drawings the booth unit A is made up of a front member 10, two side members 11 and a rear member 12. These members can be collapsed and folded together into a compact state as illustrated in Figure 5 for shipment or so that they can be stored away in a small space.

The front member 10 is provided with a panel member 13 formed of wall board or other suitable material which is held in the frame of the front member which is made up of the two upright members 14 and 15 and a lower cross member 16, together with the upper cross member or top 17. The cross member 16 is positioned or spaced from the

lower end of the uprights 14 and 15 so as to provide a space B beneath the same when the front member is set up on the floor.

The top member 17 extends out from the frame which holds the front panel 13 to provide the upper cross member 18 for the doorway 19 of the unit. This member can be shortened so as to make a wide or narrow door as may be desired in setting up the unit 10 booths A.

The side members 11 of my booth units are composed of the two panels 20 and 21 which are formed of wall board or other suitable material and which are held in the frame which is made up of the upright members 22 and 23 positioned in either side of the panels. A cross member 24 extends between the members 22 and 23 and is spaced the same distance from the lower end of the 15 members 22 and 23 as the cross member 16 of the member 10. The positioning of the member 24 in the same relative position as the member 16 from the floor is for the purpose of making a uniform construction and 20 to provide the same space B beneath the side members of the unit as is provided in the front.

The top member 25 extends across the panels 20 and 21 and is provided with an 30 outwardly extending portion 26 to form the top of the doorway 27 and which is connected on its outer end with the upright member 28. The upright member 28 forms the other side of the door opening 27 and is 35 adapted to be connected in a suitable manner to the member 15 of the front so that these members are rigidly connected together to form a booth unit A.

The member 15 is preferably half the 40 thickness of the member 28 so that it can be attached by screws or nails to the member 28 and so as to keep a uniform width across the front. In this manner my booth units 45 A are practically square when set up. Obviously the doorway 27 can be made narrower by shortening the member 26 and moving the member over closer to the member 22.

The back member 12 is formed of three 50 panels 29, 30 and 31 which extend down practically to the floor and are held in the frame made up of the upper cross member 32 and the lower cross member 33, while the 55 ends are provided with upright members 34 and 35. These members are narrower than the members 23 of the sides and adapted to fit between and attach to the same, as illustrated in Figure 3. The narrower construction of the members 34 and 35 is similar to the construction of the member 15 so as to 60 make up the proper dimensions of the booths A.

The panels 29, 30 and 31 are separated by the upright members 36 and 37 which extend between the members 32 and 33. Across 65

the back of the center panel member 30 are provided two reinforcing members 38 and 39 which are positioned in a manner so as to permit a mirror or other articles to be readily secured to the back member 12. It is evident that as many of these reinforcing members 38 and 39 as desired may be used to provide a back member adapted for the most effective use in the making up of my booth units A.

The booth units A are provided with the doorways 19 and 27 so that where a series of these units are used, as illustrated in Figures 1 and 2, they are intercommunicative by the users of the same through the doorways 27. Naturally these doorways can be closed by suitable curtains so as to make the booths practically private from each other and the uniform construction provides booth units for barber chairs or the like where hair bobbing and Marcelling can be readily carried on in each booth. This provides a very desirable arrangement for barber shops where the majority of the customers constitute men coming for a hair cut and shave and where a lady does not ordinarily care to go and have her hair bobbed or cared for. These private booths also provide a very practical means for the barber to take care of all of his customers, so that their work 95 can be done practically private from the other barber chairs. The front doorway 19 can also be closed by suitable curtains or ordinary construction which are not illustrated in the drawings. In this manner the booths 100 A form private compartments for each of the barbers and it has been found that with this arrangement the barber is in a position to serve the customer better and the customer is very apt to use more service than where 105 the chairs are in open communication with each other.

All of the sides of the booth units A are the same, which is also true of the front members 10. This simplifies the construction of my booth units all the more, for the reason that the backs are all the same and thus by means of two sides 11, a front member 10, and a back member 12, a single unit, or by using a series of these members, any 115 number of units can be set up together as illustrated in Figure 1.

In many instances the back member 12 is not desired. When this is the case the members 10 and the side members 11 can be connected together and equally well form individual booth units to make the private compartment for each barber. In this instance where the back member is not used the end members 23 are secured to the wall 125 or set up against the same so as to properly position the units in relation to the side wall of the room in which the booths are set up.

While I have illustrated a particular form 130 of each of the members of my booth units, I

desire to have it understood that this is only illustrative and that the invention can be carried out by other means and applied to uses other than those above set forth within the scope of the following claims.

I claim:

1. A collapsible booth unit including a front member, side members having the same general formation, a doorway formed in said front member, a lintel attached to said front member adapted to be shortened to change the width of said doorway, doorways formed in said side members and a solid back member whereby the members of said booth unit can be collapsed into a compact state or set up to form communicating doorways to each booth and private doorways into each booth.
2. A booth unit including front, side and back members collapsible into a compact state and adapted to be set up in a manner to form a series of units when the respective parts are connected together to provide a single private barber booth or a series of intercommunicating booths, all of the respective front portions and the respective side members of the respective booths being of the same general formation.
3. An adjustable collapsible booth unit including front, side and back members adapted to be folded together into a flat, compact state, doorways formed in the front

and side members, a lintel extending from said front member which is adapted to be shortened by removing a piece thereof to 35 change the width of the front doorway and size of the booth unit, said side and front members having panel frames spaced at equal distances from the bottom to form a space beneath the same when the booth unit 40 is set up.

4. A collapsible booth unit including front and side members, panel frames formed in said members spaced from the bottom of said front and side members in a 45 manner to form a passageway beneath the same, doorways formed in each of the side and front members, said doorways permitting intercommunication between similar booths set up adjacent each other and private doorways in the front of each booth, said booth units being adapted to be connected in a manner so as to position the location of the doorways in the front and side members adjacent each other. 55

5. A collapsible booth unit including a front member, side members comprising a panel section and a doorway, a lintel integral with said front member extending from said front member and adapted to be detachably 60 attached to one of said side members thereby defining a doorway.

ALFRED J. KRANK.
